CLAIM

The ornamental design for a pair of tire segment ends for a seam joint on a replaceable tire, as shown and described.

DESCRIPTION

FIG. 1 is a perspective view of the right side, top, and front side of a pair of tire segment ends for a seam joint on a replaceable tire showing the new design.

FIG. 2 is a perspective view of the left side, top, and front side thereof.

FIG. 3 is a perspective view of the left side, bottom, and front side thereof.

FIG. 4 is a perspective view of the right side, bottom, and front side thereof.

FIG. 5 is a front side elevational view thereof which allows views through the three unobstructed through hole pathways that connect the front side to the back side.

FIG. 6 is a rear side elevational view thereof which allows views through the three unobstructed through hole pathways that connect the back side to the front side.

FIG. 7 is a right side elevational view thereof.

FIG. 8 is a left side elevational view thereof.

FIG. 9 is a top plan view thereof.

FIG. 10 is an enlarged perspective view of the bottom, front side view of the pair of tire segment ends on a portion of the tire segment.

FIG. 11 is an enlarged perspective view of the top and right side of the pair of tire segment ends on a portion of the tire segment.

FIG. 12 is an enlarged perspective view of the top and left side of the pair tire segment ends on a portion of the tire segment.

FIG. 13 is an enlarged perspective view of a top, right side, and front side view of a cross section of the male tire segment end on a portion of a tire segment.

FIG. 14 is an enlarged perspective view of a top, front side and left side view of a cross section of the pair of tire segment ends on a portion of the tire segment; and,

(Continued)

FIG. 15 is another perspective view of a top, front side view of a pair of tire segment ends for a seam joint on a replaceable tire, shown in alternate use.

The broken lines in the drawing depict portions of the pair of tire segment ends for a seam joint on a replaceable tire that forms not part of the claimed design. The dot-dot-dash lines are to show boundaries and form no part of the claimed design.
